CASING FOR AN AEROSOL-SPRAY DISPENSER

Ralph E. Kruck, Clinton, Conn., assignor to Metal Fabrications, Inc., Waterbury, Conn., a corporation of Connecticut

Filed Dec. 28, 1960, Ser. No. 63,368

Term of patent 14 years

(Cl. D83—1)

FIG. 4.

FIG. 3.

FIG. 1.

FIG. 2.

FIG. 1 is a front perspective view taken from the top and one side of a casing for an aerosol-spray dispenser embodying my new design;

FIG. 2 is a front elevational view thereof;

FIG. 3 is a top plan view thereof, the bottom being substantially plain; and

FIG. 4 is an enlarged vertical fragmentary sectional view of the upper portion of the casing, the section being taken along line 4—4 of FIG. 3.

I claim:

The ornamental design for a casing for an aerosol-spray dispenser, substantially as shown and described.
